UNITED STATES PATENT OFFICE.

JOSEPH F. SPIEGEL, OF TORONTO, ONTARIO, CANADA.

STEAM-GENERATING PLANT.

1,308,122.

Specification of Letters Patent.

Patented July 1, 1919.

Application filed March 16, 1917. Serial No. 155,264.

To all whom it may concern:

Be it known that I, JOSEPH F. SPIEGEL, a citizen of the United States of America, residing in the city of Toronto, county of 5 York, Province of Ontario, Canada, have invented certain new and useful Improvements in Steam-Generating Plants, of which the following is a specification.

This invention relates particularly to 10 means for firing locomotive and other boilers so that they will be smokeless in operation, efficient and economical, silent and requiring a minimum of attention from the fireman.

15 I attain my objects by means of the constructions hereinafter described and illustrated in the accompanying drawings in which—

Figure 1 is a longitudinal section showing 20 a locomotive boiler arranged in accordance with my invention;

Fig. 1^a shows the tender and its equipment and is complementary to Fig. 1;

25 Fig. 2 a cross section of the tender; and Fig. 3 a front elevation of the tender.

In the drawings like numerals of reference indicate corresponding parts in the different figures.

The drawings are to a considerable extent 30 diagrammatical and the mechanical constructions may be considerably varied without departing from the spirit of my invention.

1 is the boiler, which is shown as of the 35 fire tube type and provided with a fluid burner, which is preferably, though not necessarily, of the type shown and provided with a jet 2 located opposite each fire tube. These jets are each preferably provided with 40 a conical spreader 3 intended to produce a cylindrical jet of flame.

Each jet has a mixing chamber 4 located at its rear end, which mixing chambers communicate by means of pipes 5 with alternating 45 air and gas conduits 6 and 7 supported by a burner frame suitably supported close to the rear tube plate of the boiler. Air is supplied to the air conduits by the air pipe 42 connected to the conduits and supplied with air by suitable compressing 50 means, (not shown).

Gas is supplied from the supply pipe 8

which connects with each gas conduit and leads from the producer gas generator 9 on the tender, which generator is hereinafter 55 more specifically described.

In the gas supply pipe and also in the air supply pipe is located a manually controllable valve 10, both arranged to be simultaneously controlled by a single handle. In 60 each pipe there is also provided an automatic regulating valve 11 controllable by steam pressure from the boiler, but as these are well known in the art, they are not illustrated in detail.

The tender forms a feed water tank and the generator is arranged so that it is completely jacketed by the water in the tender, so that the waste heat from the generator 65 is used to heat the feed water.

The generator is of the hopper type and is provided with sufficient gas space 12 to give a small reserve. The gas supply pipe communicates with this space and preferably forms a coil within the gas space. A 70 further reserve tank 43 is preferably provided on top of the tender communicating with the gas space 12.

The generator is provided at its lower end with a fire door 13 for re-lighting, and a 75 long narrow door 14 through which the height and condition of the fuel may be examined. 15 is the grate, of any ordinary type, below which is located a suitable inclosed ash pan 16. A pipe 17 leads into the 80 ash pit for supplying steam and air to the generator. With this pipe connects a pipe 18, which will lead to any suitable source of compressed air.

With the pipe 17 also communicates a 85 pipe 19 from the boiler. The three pipes 17, 18 and 19 are each preferably provided with an automatic regulating valve 20 adapted to be controlled by gas pressure led thereto by the piping 44.

The feed water space of the tender is connected by means of a pipe 21 with the boiler and an inspirator 22 or other suitable device is used in this pipe to feed the water to the boiler. The exhaust steam pipe 23 from the 95 valve chests of the locomotive leads into the tender and its upper end is led into a condensing chamber 24, which chamber at its lower end communicates by means of open-

ings 25 with the water space of the tender. A drainage cock 45 is preferably provided in the pipe 23.

At the lower part of this condensing chamber I provide a number of splash bars 26. These are preferably V-shaped as shown 26. These are preferably V-shaped as shown and slightly clear the bottom when hanging straight. When slightly rocked they 10 act efficiently as splash bars and at the same time permit of water and sediment passing freely underneath them when they are hanging straight.

A plurality of clean-out plugs 27 are preferably located close to the bottom of the 15 walls of the tender.

The condensing chamber is provided at its upper end with a safety valve 28, preferably of the spring type, to relieve any excess pressure which might accumulate in 20 the chamber. A manually operable valve 29 is also provided by means of which any pressure may be relieved and which may also be used to allow any oil that may collect in the condensing chamber to flow out 25 when refilling the tender with water.

Into the water space of the tender extends the filling tube 30, preferably frusto-conical as shown. The lower end of this tube is formed with a valve seat engageable by the 30 downwardly opening valve 31, the stem of which is suitably guided. This valve is normally pressed to its seat by the coil spring 32 engaging a supporting frame work 33 and the under side of the valve. This valve 35 will yield to the weight of water flowing down through the filling tube but will close to prevent egress of steam or water.

To indicate the pressure in the water tank I provide the pressure gage 34 communicating 40 with the water space. To indicate gas pressure I provide the pressure gage 35 communicating with the gas space 12. This gas space is also provided with a suitable safety valve 36 to relieve excess pressure. A water 45 gage 37 is also preferably provided to indicate the water level in the tank.

As the exhaust steam is no longer available to create a draft, I provide mechanical means in connection with the draft pipe 38 50 to create the necessary draft. For this purpose I employ a fan 39 projecting into the draft pipe and driven by a steam turbine or other suitable motor supplied with steam from the boiler.

55 A hinged damper 41 is preferably provided at the lower end of the draft pipe and may be operated by any suitable mechanism.

The operation of the plant is substantially as follows. The generator is started in operation and suitably supplied with fuel and any air and steam necessary to satisfactorily start it in operation may be supplied from extraneous sources, after which it will be supplied with steam from the boiler and 65 with air, as may be necessary, from an air

compressing plant provided for that purpose. As soon as gas is generated, it passes away under pressure through the supply pipe 8 and is burned at the jets 2, thus generating steam in the boiler, the products of 70 combustion being drawn through the fire tubes preferably by mechanically created draft as hereinbefore described.

The exhaust steam from the cylinders is led to the condensing chamber and is there 75 condensed, giving up its heat to the feed water. Otherwise waste heat from the generator is also taken up by the feed water.

To conserve the heat of the feed water as much as possible, the tender is preferably 80 suitably lagged. As may be necessary feed water is added through the filling tube 30 to replace any waste, and also as may be necessary oil accumulating in the condensing chamber may be floated off through the man- 85 ually operable valve 29.

The advantages of the constructions and arrangements I have above described are numerous, but it will suffice to enumerate a few of them. In operation the device will 90 be entirely smokeless, as the gas generated is burnt under conditions which insure perfect combustion. The loss of heat in the exhaust by radiation from the fire box in ordinary locomotives or furnaces is almost en- 95 tirely avoided. The labors of the fireman are very considerably reduced, as the generator is self-feeding and its hopper may be mechanically filled or emptied. With this device almost any grade of fuel may be used to 100 advantage. Perfect regulation of the firing can be obtained automatically and manually. The elimination of the firebox not only strengthens the construction of the 105 boiler as hereinbefore referred to, but permits of a considerable increase of the heating surface.

It will be understood, of course, that the details of the construction may be very considerably varied without departing from the 110 spirit of my invention.

What I claim as my invention is:—

1. The combination of a boiler; a fluid burner for firing the same; means for utilizing the energy of steam generated by the 115 boiler; an exhaust steam pipe; a feed water tank separated from the boiler; a pipe leading therefrom to the boiler; means for condensing steam from the exhaust pipe to mingle with the feed water; a producer gas 120 generator located within the tank so as to be jacketed by the water therein; a supply pipe leading from the generator to the fluid burner, and an automatic valve in said gas supply pipe controlled by the steam pressure in the boiler.

2. The combination of a boiler; a fluid burner for firing the same; means for utilizing the energy of steam generated by the 125 boiler; an exhaust steam pipe; a feed water 130

tank separate from the boiler; a pipe leading therefrom to the boiler; means for condensing steam from the exhaust pipe to mingle with the feed water; a producer gas generator located within the tank so as to be jacketed by the water therein; a supply pipe leading from the generator to the fluid burner; an automatic valve in said gas sup-

ply pipe controlled by the steam pressure in the boiler; a steam pipe leading to a point 10 below the grate of the producer; and an automatic valve in said steam pipe controlled by the gas pressure in the producer.

Signed at Toronto, Canada, this 6th day of March, 1917.

JOSEPH F. SPIEGEL.
